UNITED STATES PATENT OFFICE

2,513,567

DISHWASHER.

Frederick W. Kent, Milwaukee, Wis.

Application June 4, 1947, Serial No. 752,305

4 Claims. (Cl. 299—84)

1

This invention relates to a dish washer.

The invention is of the general type of dish washer which is attached to a faucet and contains a bar of soap, wash water being directed over the soap and then onto the dishes to be washed, which may be held in a tray in the sink. A flexible hose and spray means is included for spraying the water directly onto the dishes. It is a small device and can be attached quickly to the faucet, and when not in use, may be taken off and the faucet then used in the ordinary manner. The device includes a valve which in one position directs water through the device and on to the soap and then on to the dishes; in another position of the valve, water is by-passed around the soap for rinsing the dishes; and in a third position of the valve, the device is drained.

An important object of the present invention is an arrangement for producing an intense sudsing action with a minimum amount of water used. This action is accomplished by directing the water onto the soap many times in passing through the soap chamber. Included in this arrangement is the elimination of solid streams of water being directed onto the soap; instead, the wash water is directed onto the soap from all angles, contacting a greater area of the soap, and augmenting the sudsing action.

Another important feature of the present invention is a simple and efficient valve for controlling the passage of the water, that is, through the soap container or by-passing the soap container.

Still another advantageous feature of the invention is an improved means for attaching the device to a water faucet.

An additional advantage is a new dish spray means for directing the water onto the dishes. This spray means is so correlated with the means for directing water onto the soap, that a certain amount of the pressure built up in the device is dissipated, and serious splashing effect on the dishes is eliminated.

Still another advantage is a new type of heat insulator for holding the flexible hose and dish spray means. When hot water is sent through the device, the flexible hose and dish spray means becomes hot, and my new type of insulator enables the user to grasp the hose without feeling the heat from the water.

With these and other objects in view, my invention consists in the construction, arrangement and combination of the various parts of my device whereby the objects contemplated are attained; as hereinafter more fully set forth, point-

2

ed out in my claims and illustrated in the accompanying drawings, in which:

Fig. 1 is a side view of the dish washer of my invention;

Fig. 2 is a top view of the device;

Fig. 3 is a bottom view of the same;

Fig. 4 is an enlarged vertical sectional view of the dish washer;

Fig. 5 is a fragmentary sectional view showing the manner of attaching a flexible hose to the soap container;

Fig. 6 is an enlarged sectional view of the insulator for the flexible hose;

Figs. 7, 8 and 9 show different positions of the valve for controlling the flow of wash water.

Figs. 10 and 11 show modified spring clamps for securing the cover for the soap chamber in place, and for securing the dish washer to the faucet; and

Fig. 12 is an enlarged view taken on line 12—12 of Fig. 10.

Referring in detail to the drawings, the device is shown applied to a water faucet 12, and includes as its principal elements, a dish washer proper 14, an inlet tube 16, and a flexible hose 18 forming an outlet. The device includes a circular base 20; a bottom extension 21 and having a flared wall 22 extending upwardly and outwardly from the bottom extension 21. The flared wall 22 terminates in axially extending flanges 24 and 26 which form an annular channel 28. A dome 30, preferably of glass or other transparent material, is seated on a sealing means 32 placed in the channel 28, and forms a soap container 33 with the base 20. A yoke 34 formed of spring material; and having a turned-in extension 36 on each end, is secured to the base 20, the extensions 36 fitting into openings 38 on opposite sides of the base. A lever and cam device 40 is secured on the yoke 34 and engages in a depression 44 in a projection 42 on the top of the glass dome 30, for securing the dome in place on the washer.

The base 20 is provided with a centrally upwardly extending boss 46 surrounding which is an annular depression 47. The boss 46 has a central threaded opening 48 for the reception of a stud 50. Welded to the upper end of the stud 50 is a hollow plate 52. The periphery of the upper surface of the hollow plate 52 is bevelled as indicated at 53.

The undersurface of the bottom extension 21 of the base 20 has formed therein a circular recess 54 for the reception of a disc valve 56, which is closed by a cap 58. The valve 56 has an axial dimension less than the recess 54 and is held in

place in the recess by means of a projection 60 formed on the inner surface of the cap 58. The surrounding surfaces of the recess 54 and the projection 60 form a liquid tight seal for the valve 56; no packing is necessary to seal it further and a shim 61 is interposed for accurately spacing the cap 58.

Wash water leading from the tube 16 enters through bore 62 in the cap 58, then through various passages in the valve 56, which will be described later, then through bore 64 formed centrally of the boss 46, and finally through bore 66 in the stud 50. From the bore 66 the water emerges into the interior of the hollow plate 52 from which it passes into the interior of the dish washer, through a plurality of holes 68 formed in the bevelled surface 53 and spaced around its periphery. A cake of soap 70 is placed on the hollow plate 52 over which the wash water passes.

When the device is in use the level of water therein rises to approximately the level of the line 71, or, a short distance above the holes 68. The reason for this, and the result, will be described later.

The wash water after passing over the soap and forming suds, is discharged out through the passages in the valve 56 into opening 72 formed radially in the bottom extension 21 of the base 20. The flexible hose 18 leads from the opening 72, being secured thereto by means of a spud 76. The hose 18 has fixed on its outer end a nozzle 78 by means of another spud 80. The nozzle 78 has a plurality of openings 82 formed in its outer end. An insulating device in the form of a cylindrical piece of tubing 84 surrounds and is attached to the nozzle 78, as indicated at 86, and covers a portion of the flexible hose 18. The section of tubing 84 is spaced from the hose 18 the greater part of its distance for insulating the hand of the user against heat from the hot water used in washing dishes. The hose 18 and insulator 84 may be of any material which is flexible, but in the present case plastic is preferably employed.

A horizontal extension or leg 88 is secured to the lower end of the tube 16 and is provided with a central bore 90 communicating with the interior of the tube 16, and at its opposite end having a vertical bore 92. An annular channel 94 is formed around the bore 92 in the upper surface of the leg 88 into which is inserted a sealing means 96 for engaging the open end of the water faucet 12. An annular ring 98 surrounds the downwardly extending portion of the water faucet 12 and is secured in place thereon by screws 100 spaced therearound. A spring yoke 102 is swingably secured in the ring 98, by means of inturned extensions, and extends below the lower surface of the leg 88. An adjusting screw 104 in the extended end of the yoke 102 engages the under-surface of the leg 88 for securing it onto the faucet 12; thus the dishwasher is supported on the faucet by the upright tube 16. When the dish washer is not in use it is removed from the faucet, the yoke 102 is swung up to the dotted line position as indicated at 106, and the faucet used in the normal manner although the ring 98 remains on it.

The construction of the valve 56 is shown in section in Fig. 4, and in Figs. 7, 8 and 9, the latter figures showing the various operating positions of the valve. The valve is provided with an axial bore 112 positioned radially to register with the bore 62 leading from the inlet tube 16.

Communicating with the bore 112 and formed in the upper surface of the valve is a radially extending groove 114 leading to the center of the valve where it registers with the bore 64. A circumferential channel 116 is formed in the upper surface of the valve and extends a portion of the periphery thereof. At one end of the channel 116 is an opening 118, and at the opposite end is another opening 120, both of which extend axially through the valve. Formed centrally of the lower surface of the valve 56 is a squared recess 122 adapted to receive a squared head 124 on the upper end of a shaft 126, which is rotatably mounted centrally in the cap 58 and extends therethrough. A handle 128 is fixed in the lower end of the shaft 126 for rotating the shaft and the valve.

A bore 130 leads downwardly from the annular depression 47, communicates with the peripheral channel 116 in the valve 56 in certain positions of the valve, and provides an outlet from the chamber 33. Another bore 132 leads downwardly from the annular depression 47, and registering therewith is a bore 134 in the cap 58. In a certain position of the valve 56, the opening 120 registers with both the bores 132 and 134 and provides a vent for draining the container 33.

The area of the opening of the bore 130 is less than the total area of the holes 68; similarly, it is less than the total area of the openings 82 in the nozzle 78. The effect of these relationships will be described later.

Figs. 10, 11 and 12 show a modified form of clamping yoke for clamping the dome 30 onto the dish washer, and a similar yoke for clamping the dish washer onto the faucet.

The reference numeral 136 indicates the yoke for clamping the dome 30, and comprises a bail member T-shape in cross section having inturned ends 138. The inturned ends 138 engage in projections 140 formed on the underside of the margin of the flared wall 22 on opposite sides thereof. The projections 140 are formed with depressions for accommodating the inturned ends 138. The top of the yoke 136 is formed with a thumb screw 142 threaded therethrough, which is adapted to engage a depression in a projection 144 formed on the top of the dome 30. This type of yoke has the advantage that it can be removed entirely from the dish washer, and in addition it possesses great strength for withstanding the pressure developed in the dome 30.

The yoke 146 for securing the dish washer onto the faucet comprises a flat spring metal member having inturned ends 148, which are adapted to engage projections 150 formed on the upper surface of the ring 98. The inturned ends 148 are curved transversely, and the projections 150 have depressions formed therein for accommodating this curvature. The lower end of the yoke 146 is formed with a reinforcing member 152, having a central threaded bore for accommodating the thumb screw 104. To secure the dishwasher to the faucet, the terminal end of the leg 88 is fitted under the open end thereof, the yoke 146 is applied thereto, and the thumb screw 104 tightened. In removing the dish washer from the faucet, the yoke 146 is removed entirely and thus the faucet may be used in the usual way without hindrance by a swinging yoke.

The ring 98 in this modification, that is, Figs. 10 to 12, is secured at the lower extremity of the faucet, and being spaced circumferentially from the faucet, it serves as a guiding means for centering the sealing means 96 on the faucet, and

in this manner the dish washer can be quickly attached.

Use and operation

Figs. 7, 8 and 9 show the various positions of the valve 56 in the different operations of the device. These figures are oriented to agree with Fig. 2, so that in describing the positions of the valve they may be compared with Fig. 2 as being superimposed thereon.

Fig. 8 shows the valve in "sudsing" position, that is, the wash water enters into the dish washer and washes over the soap and is then discharged through the nozzle onto the dishes. This is the position also which is shown in Fig. 4, the wash water passing through the bores 62, 112, 114, 64, and into the interior of the chamber 33 of the dish washer and onto the soap, forming suds. The water then passes through bore 130, into channel 116, and then passes out through the opening 72, through the flexible hose 18, and ultimately onto the dishes to be washed. The bore 130 is indicated as being superimposed on Fig. 8.

The method of directing the water onto the soap in the present invention is an entirely new concept, one of the objects being to disintegrate the soap fast for producing a great amount of suds, and still not use an excessive amount of water. Another object is to prevent solid and penetrating streams of water from being forced directly onto the soap. The latter causes undue penetration through the soap without the benefit of proper sudsing action, since the area of the soap contacted by the water is not so great, and disintegration of the soap in fine particles does not occur.

The total area of opening of the holes 68 is greater than the opening of the outlet bore 130 and for this reason the water level in the device in normal operation rises to the line indicated at 71. As the water level rises, the air in the container 33 is compressed, and this forces the water out the hole 130 at a faster rate, maintaining the level at approximately the level indicated. It will be noted that this level is above the holes 68 and this comprises an important aspect of this invention. Water emerging from the holes 68 spreads to a considerable extent and picks up and carries with it water which is resting in the bottom of the container 33. By this method a great amount of water is directed onto the soap, and many times, causing rapid disintegration of the soap and forming a large amount of suds. This water is churned over and over and causes an intense and persistent turbulence in the container. At the same time, water is being driven out, but before it is driven out, it is washed against the soap many times. Thus a maximum amount of suds is obtained with a minimum of water used.

Wash water on emerging from the holes 68 in the hollow plate 52 is directed against the interior of the dome 30 as shown in Fig. 4, the peripheral surface 53 of the hollow plate 52 being so shaped that the holes 68 are directed toward the dome. The streams of water from the holes 68 spread somewhat and impinge on the inner surface of the dome over a considerable vertical extent as indicated roughly at the points 108. This area of course, is an approximation and not necessarily the exact area over which the streams spread. Similarly, as shown in Fig. 2, the lateral spread of the spray may cover an area between the points 110. The streams on contacting the inner surface of the dome spread circumferentially as

shown in Fig. 2, and merge with adjacent streams and are thereby directed against the cake of soap 70, as indicated by the arrows. Similarly, some of the water spreading from this area travels upwardly in the dome 30, and at the center of the top, the streams from all of the holes 68 converge and are directed onto the top surface of the cake of soap 70, as indicated by the arrows in Fig. 4.

10 It will be seen that solid streams of water are not forced directly onto the soap, causing undesirable drilling action and forming holes therethrough. Instead, it is forced onto the soap from all directions whereby a greater area of surface 15 of the soap is affected and greater sudsing action is accomplished.

The total opening of the holes 68 in the nozzle is greater than the area of opening of the outlet bore 130, whereby the wash water emerges from 20 the nozzle with less pressure than that with which it passes through the bore 130. This prevents excessive splashing when the water strikes the dishes.

Fig. 7 shows the position of the valve 56 in 25 "rinsing" position. In this position the opening 108 at one end of the channel 116 registers with the bore 62 permitting water from the tube 16 therethrough and into the channel 116. It then passes around the channel 116 and out the opening 72 into the flexible hose, from which it is sprayed onto the dishes. In this operation the water by-passes the soap chamber 33 and emerges as clear water.

Fig. 9 shows the position of the valve 56 in 30 "drain" position. As stated before, bores 132 and 134 are in alignment, and when the valve is turned to the position shown in Fig. 9, the opening 120 registers with both these bores, 132 and 134. Bore 134 is indicated as being superimposed 35 on Fig. 9. Also in this position, the channel 116 communicates with the opening 72. The operation of the drain is accomplished by providing a vent through the bores 132 and 134. This admits atmosphere to the chamber, and permits the water in the chamber to be drained out 40 through the flexible hose. The water from the soap chamber does not drain out through this opening formed by the bores 132 and 134, but the water in the hose runs out and produces a 45 siphon effect, draining the chamber.

50 While I have shown a particular embodiment of my invention, it will be understood of course that I do not wish to be limited thereto since many modifications may be made, and I therefore contemplate by the claims appended hereto 55 to cover any such modifications or substitutions of mechanical equivalents as fall within the true spirit and scope of my invention without sacrificing any of its advantages.

60 I claim:

1. In a dish washer, a container for soap, a hollow plate for supporting soap in the container, said hollow plate having a plurality of peripherally spaced holes formed therein and directed upwardly and outwardly therefrom, means for conducting water through said hollow plate and through said holes into the container, the holes in said hollow plate being so directed that water emerging therefrom impinges on the inner 65 surface of the container and thereby onto the soap, and means for conducting water from the container.

70 2. In a dish washer, a container for soap, supporting means within the container and spaced 75 from the bottom thereof for supporting soap,

means for conducting water into the container and onto the inner surface thereof and thereby onto the soap, said container having a plurality of openings below said hollow plate, one of said openings being adapted for flow of water therethrough and onto dishes to be washed, another of said openings forming a vent for permitting the container to be drained through said one opening.

3. In a dish washer, a container for soap, said container having a central upwardly extending boss formed in the bottom thereof, there being an annular depression surrounding said central boss, a hollow plate supported in said boss for supporting soap in the container, means for conducting water through the said central boss and said hollow plate and onto the soap, means for conducting water from said container, said container having a drain vent leading downwardly from said annular depression. 10

4. In a dish washer, a container for soap, means for conducting water into the container, said container having an outlet, outlet spray means leading from said outlet and having a plurality of holes formed therein for directing 20 water onto dishes to be washed, the total area

of the holes in said outlet spray means being greater than the total area of said outlet of the container, whereby pressure built up in said container is partially dissipated when the water emerges from said outlet spray means.
